UNITED STATES PATENT OFFICE.

JAKOB PETER JAKOBSEN AND HANS FREDERIK JENSEN, OF COPENHAGEN, DENMARK:

ELECTRIC SWITCH.

1,003,111.

Specification of Letters Patent. Patented Sept. 12, 1911.

Application filed August 1, 1910. Serial No. 574,816.

To all whom it may concern:

Be it known that we, JAKOB PETER JAKOBSEN and HANS FREDERIK JENSEN, subjects of the King of Denmark, both residing at Copenhagen, Denmark, have invented new and useful Improvements in Electric Switches, of which the following is a specification.

The object of this invention is an electric switch or the like wherein a contact arm rotatable about the center of the base in a plane parallel thereto is operated by means of a lever rotatable in a plane perpendicular to the plane of rotation of the contact arm, its inner free end acting on the contact arm through a helical spring or the like connecting these two members.

The invention is shown in the accompanying drawings in which—

Figure 1 shows a plan of the switch with the outer cover removed. Fig. 2 is a section on the line II—II of Fig. 1. Fig. 3 is a plan view with the cover removed of a modification of the invention, and Fig. 4 is a section on the line IV—IV of Fig. 3.

Referring to the drawing 1 indicates the socket, 2 the contact arm, 3, 3 the contact springs 4, 4 the terminals, and 7 the switch spring connecting the switch lever with one end of the contact arm.

The manner of execution shown in Figs. 1—2 is arranged as the ordinary tumbler switches, as far as the handle lever is concerned. This latter consists of a double lever 13, 14 extending through the cover and pivoted on a pin 15 having its bearings in a bridge piece 16. The lever's inner arm 14 is bent somewhat to one side and forms an eyelet 17 wherein the end of the spring 7 is fastened, there being interposed between the eyelet 17 and the end of the spring a small insulating sleeve 18. The other end of the spring is fastened to the one upward bent end of the contact lever. When the handle lever is tipped over into its other position, the end of the spring fastened thereto will pass the pivot of the contact lever and thereby cause the latter to jump suddenly into its other extreme position shown by dotted lines, the terminals arresting it in this position, in which position the handle lever as well as the contact lever will remain stationary in consequence of the tension of the spring, until this tension is again overcome by the handle being tipped over into its other position when in similar manner the

contact lever 2 will thereby be caused to jump back into its original position where it will be arrested by a stop 10.

In the manner of execution shown in Figs. 3—4 the switch spring is arranged in exactly similar manner, its inner end being fastened to the inner arm of a lever adapted to be moved, in a plane perpendicular to the plane of revolution of the contact arm and beyond the pivot thereof by which movement it carries the inner end of the spring into one or the other of two positions to different sides of this fulcrum. On the drawing the arm of this lever is marked 19, and it is in firm connection with one of the two levers 20, rotatable about a pin 21, in a fork 22 which projects from a bridge 23 supported by the base 1. This bridge is carried by two small posts 24, 24 of U-formed cross-section forming guides for the push-buttons 25, 25 which extend out through a cover 26 fastened to the bridge 23. In the posts 24, 24 slots 27, 27 are cut for the guiding pins, 28, 28 which are fastened to the lower ends of the push-buttons and also fit into oblong holes cut out in the ends of the levers 20. In the position shown in the drawing the contact arm is out of contact, with the contact spring 3. When now the one push-button 25 projecting through the cover 26 is depressed, it will cause the lever 20 to turn, and as thereby also the arm 19 is turned, the spring 7 and consequently the contact arm 2 will jump over, and arm 2 will then connect the contact springs 3. In this position the spring 7 will maintain the contact arm 2 as well as the arm 19, the levers 20 and the buttons 25, and of these latter the one shown to the right in the drawing is now depressed, while the one to the left will have leaped out beyond the cover plate 26. When the last mentioned button is again depressed, the system will once more be reversed, that is to say the contact arm will again return to its off-position. This last manner of execution is especially designed for use in cases where it is desired to place the entire switch hidden in the wall, the cover plate 26 being then flush with the wall.

Having now particularly described and ascertained the nature of our said invention and in what manner the same is to be performed, we declare that what we claim is:

1. An electric tumbler switch, comprising a contact arm, turnable parallel to the plane of the base; a tumbler lever, turnable in

a plane perpendicular to the base, a spring connecting said contact arm to said tumbler lever and adapted to shift said arm from one position to another as said spring is actuated by said tumbler lever, for the purpose of opening or closing the switch.

2. An electric tumbler switch, comprising a contact arm, turnable parallel to the plane of the base; a tumbler lever, turnable in a plane perpendicular to the base, a spring connecting said contact arm to said tumbler lever and adapted to shift said arm from one position to another as said spring is

actuated by said tumbler lever, for the purpose of opening or closing the switch; said contact arm being retained in either of its positions by said spring, according to the position of the tumbler lever.

In witness whereof, we have hereunto signed our names in the presence of two subscribing witnesses.

JAKOB PETER JAKOBSEN.
HANS FREDERIK JENSEN.
